UNITED STATES PATENT OFFICE.

SAMUEL M. WINKLER, OF NEW YORK, N. Y.

DESIGN FOR MERCHANDISE-DISPLAY RACK.

42,427.

Specification for Design.

Patented Apr. 23, 1912.

Application filed December 16, 1911. Serial No. 666,271. Term of patent 7 years.

To all whom it may concern:

Be it known that I, SAMUEL M. WINKLER, a citizen of the United States, residing at New York city, Manhattan borough, in the county and State of New York, have invented a new, original, and ornamental Design for Merchandise-Display Racks, of which the following is a specification, reference being had to the accompanying drawing, forming part thereof, wherein—

The bags shown supported in the several compartments of the display-rack form a part of the design.

I claim:

The ornamental design for a merchandise display-rack, as shown.

SAMUEL M. WINKLER.
